CLAIM

The ornamental design for an upright vacuum cleaner, as shown and described.

DESCRIPTION

FIG. 1 is a top, front, and right-side perspective view of an upright vacuum cleaner showing our new design;

FIG. 2 is a front view thereof;

FIG. 3 is a right side view thereof;

FIG. 4 is a left side view thereof; and,

FIG. 5 is a top view thereof.

The broken lines illustrate portions of the upright vacuum cleaner that form no part of the claimed design.
